UNITED STATES PATENT OFFICE.

FREDRICK A. LAROCHE, OF PHILADELPHIA, PENNSYLVANIA.

BRUSH-HOLDER FOR DYNAMO-ELECTRIC MACHINES OR MOTORS.

SPECIFICATION forming part of Letters Patent No. 425,435, dated April 15, 1890.

Application filed December 7, 1889. Serial No. 332,934. (No model.)

To all whom it may concern:

Be it known that I, FREDRICK A. LAROCHE, a citizen of the United States, and a resident of the city of Philadelphia and State of Pennsylvania, have invented a new and useful Improvement in Brush-Holders for Dynamos or Motors, of which the following is a clear and sufficient specification, reference being had to the drawings annexed.

10 My invention relates principally to brush-holders intended to be used with carbon or other rigid or inelastic brushes, but can be used with advantage also with other brushes now in use.

15 In the present form of brush-holders the brush is held without any provision for lateral adjustment except the elasticity of the brush itself. On this account the brushes are usually made of thin strips of copper or 20 other elastic conductor, as carbon or other rigid brushes, though used, required an extremely careful adjustment to make an even contact between the commutator and the brush, because if they do not lie flat against 25 the commutator, and thus make an even contact, the commutator wears unevenly and the machine sparks. To make an even contact and to enable the brush to lie automatically flat against the commutator is the object of 30 my invention, which consists, essentially, in making the clamp holding the brush automatically adjustable, as will be now more particularly described.

Figure 1 shows an end view of a brush-holder containing my invention and the adjacent parts of a dynamo. Fig. 2 is a side view of a part of a brush-holder containing my invention. Fig. 3 shows the brush and commutator, the dotted lines showing the various positions in which the brush might be. Fig. 4 is a sketch of a modification of my invention.

I attach to the frame of a dynamo or motor of any common type a brush-holder, which I have shown in Fig. 1, of the common adjustable form as to the supporting portions, which consist, as shown, of the rocker-arms B B, vibrating on the spindle U, to which it may be clamped at any desired angle by the set-screw 50 D, and having backwardly-extending spindles E E, on which are placed the yokes F F, that are impelled inwardly by the tension-

springs G G. These parts, however, are all well known, and form no limitation upon my invention, which may be applied to the supporting portion of any form of brush-holder. To this portion of a brush-holder (to the yoke B, as shown in my illustrations) I attach the clamp I, in which I secure the brush, so as to allow a free oscillatory movement of the latter in the direction of its width. This I effect in practice by pivoting the clamp to the yoke F, preferably, though not necessarily, at a right angle with the rocker-arm, by a pivot or equivalent device. A modification is shown in Fig. 65 4, in which the desired automatic adjustability of the brush-holder is obtained by attaching the clamp holding the brush to suggest itself to a workman skilled in the art—as, for instance, by fastening it (see Fig. 4) to a spring H, the other end of which I have shown fastened to the spindle E of a brush-holder. This spring H can take the place of the tension-spring G, while its sidewise oscillations accomplish the same results as the pivot 75 shown in Fig. 3. In this clamp I is secured the brush K, which I generally make of a piece of carbon. The advantages of the use of this material are well known, but have not hitherto been made much use of on account 80 of the difficulty of adjusting it in the ordinary rigid brush-holder, caused by its inelasticity. I do not, however, limit myself to a brush of carbon, as the advantages of my invention extend equally to a brush of a rigid piece of 85 copper or other conducting material; or, if desired, the ordinary brush can be inserted.

It can readily be seen that a brush placed in a brush-holder having an oscillating motion, as above described, will adjust itself so 90 as to lie flat against and make an even contact with the commutator if placed in any of the positions shown by the dotted lines in Fig. 3, and will be aided to fall into position by the rotation of the commutator, and that 95 though it is preferable that the clamp oscillate substantially in a plane parallel to the axis of the commutator and be placed directly opposite the latter very large variations can be made without interfering with the capacity of the brush-holder to allow the brush to adjust itself and to make an even contact with the commutator.

I operate my machine as follows: In the

clamp I, I secure the brushes K K, which, if they are made of carbon or other rigid material, I preferably make extend far enough out from the clamps to bring the flat portion 5 into contact with the commutator if their ends are rough. I then start the machine. The brushes immediately adjust themselves, so that there is no sparking or wearing of the commutator, and do this even if the level of 10 the latter is not perfect, either through wear or defective construction.

What I claim, and desire to secure by Letters Patent, is—

1. The combination, with the commutator 15 and frame-work of a dynamo or motor, of a rigid brush lying in a plane tangent to the commutator and a brush-holder attached to said frame-work and freely and automatically movable in two intersecting planes, sub- 20 stantially as described.

2. The combination, with the commutator and frame-work of a dynamo or motor, of a rigid brush lying in a plane parallel to a plane tangent to the surface of the commutator, a brush-holder freely and automatically movable in two intersecting planes, and a spring impelling the brush down on the commutator, substantially as and for the purpose set forth. 25

3. The combination of the commutator and frame-work of a dynamo or motor with a brush-holder consisting of a supporting-piece attached to said frame-work, freely and au- 30

tomatically movable in a plane substantially perpendicular to the axis of the commutator, 35 and a clamping-piece attached to said supporting-piece, freely and automatically movable in a plane substantially parallel to the axis of the commutator, substantially as and for the purpose set forth. 40

4. The combination, with the commutator and frame-work of a dynamo or motor, of the supporting portion of a brush-holder, freely and automatically movable in a plane substantially at right angles with the axis of the 45 commutator, a spring operating to yieldingly impel the brush down upon the commutator, and a clamping portion freely and automatically movable in a plane substantially parallel to the surface of the commutator, sub- 50 stantially as and for the purpose described.

5. The combination, with the commutator and frame-work of a dynamo or motor, of a rigid brush lying wholly in a plane parallel to a plane tangent to the surface of the commutator and a brush-holder freely and automatically movable both in a plane substantially at right angles with the commutator-shaft and in a plane substantially parallel to the surface of the commutator, substantially 55 as and for the purpose set forth. 60
